UNITED STATES PATENT OFFICE

138,286

DESIGN FOR A SWIMMER'S MASK

Charles H. Wilen, Laguna Beach, Calif.

Application April 18, 1944, Serial No. 113,301

Term of patent 14 years

(Cl. D83—1)

To all whom it may concern:

Be it known that I, Charles H. Wilen, a citizen of the United States, residing at Laguna Beach, in the county of Orange, State of California, have invented a new, original, and ornamental Design for a Swimmer's Mask, of which the following is a specification, reference being had to the accompanying drawings forming a part thereof.

In the drawings:

I claim:

The ornamental design of a swimmer's mask, substantially as shown.

CHAS. H. WILEN.
